(57) **CLAIM**

The ornamental design for a motorcycle and/or replica thereof, as shown and described.

DESCRIPTION

FIG. 1 is a front and right side perspective view of a motorcycle and/or replica thereof showing our new design; FIG. 2 is a rear and left side perspective view thereof; FIG. 3 is a right side elevational view thereof; FIG. 4 is a left side elevational thereof; FIG. 5 is a top plan view thereof; FIG. 6 is a front elevational view thereof; FIG. 7 is a rear elevational view thereof; FIG. 8 is a bottom plan view thereof; FIG. 9 is a front and left side perspective view thereof; and, FIG. 10 is a rear and right side perspective view thereof. The broken lines in the drawings illustrate portions of the motorcycle that forms no part of the claimed design.

1 Claim, 10 Drawing Sheets
